PAUL M. STIVENDER, OF WEST ALLIS, WISCONSIN, ASSIGNOR TO ALLIS-CHALMERS
MANUFACTURING COMPANY, OF MILWAUKEE, WISCONSIN, A CORPORATION OF
DELAWARE

AUTOMATIC SYNCHRONIZER

Application filed December 5, 1929. Serial No. 411,947.

This invention relates to automatic synchronizers.

One of the objects of the invention is the provision of means which will connect two alternating current sources when they have the same frequency and are in phase. Another object is the provision of means in which the connection of the two sources is made dependent upon the time rate of change of the phase angle between said sources. Another object is the provision of means in which the connection of the two sources is made dependent on the time rate of change of relative frequency as between said sources.

Still another object is to provide a synchronizer in which the chances for the connection of the sources is increased, and more particularly, in cases where the time rate of change of phase angle remains small for but a short time, thereby shortening the time it takes for the sources to be connected after the control has been initiated.

It is also an object to provide a synchronizer in which the chances that the sources will be connected when they are out of phase are minimized.

A further object is the provision in a means for connecting two sources when they have the same frequency and phase of a means which will prevent the reconnection of said sources when the connecting means has been opened, if said sources are out of phase.

A still further object is to minimize the effect on the time of connection of the sources with regard to their frequency and phase relations, of the maximum voltage of the line or generator electromotive forces or both. It is also an object to provide a synchronizer in which a predetermined inequality in the electromotive forces of the sources when they are substantially in phase will prevent the connection of the sources. Other objects will appear hereinafter as the description of the invention proceeds.

The novel features of the invention will appear from this specification and the accompanying drawing forming a part thereof showing one embodiment of the invention, and all these novel features are intended to be pointed out in the claims.

In the drawing:

Fig. 1 is a diagrammatic showing of one embodiment of the invention.

Figs. 2 and 3 are views of details; and

Fig. 4 is a diagram of certain electromotive forces and time relations relating to the mode of operation of the invention. 55

In this specification the terms "alternating current" and "electromotive force" will be abbreviated to A. C. and E. M. F. respectively. 60

Referring to Fig. 1, an A. C. generator 1 is shown connected to conductors 2 which may be connected by means of a circuit breaker 3 to an A. C. line 4. The line 4 leads 65 to another source or sources of A. C., not shown. The circuit breaker 3 is provided with an operating coil 5 whereby the circuit breaker may be closed. In the closed position the circuit breaker is here shown as 70 held by a latch 6 which may be tripped by a trip coil 7. The trip coil 7 may be energized in response to any desired condition.

Across two of the conductors 2 leading from the generator is connected a transformer 8, and across the corresponding conductors of the line 4 is connected a transformer 9. One of the terminals of the secondary of transformer 8 is connected to a control bus 10, the other terminal being connected to a conductor 11 which is connected to a tap 13 on the secondary of transformer 9. One of the terminals of the secondary of transformer 9 is connected to a control bus 12. The connections of transformers 8 and 9 to the buses 10, 12 is such that when the generator and line are in phase the E. M. F. across these buses will be zero. 80

A relay 14 is here shown as having contacts 15 and 16 interposed in the control buses 12 and 10, respectively. The relay 14 may have one terminal connected to control bus 10 at the left of contact 16, the other terminal being connectible through a switch 41 and an auxiliary switch 42 to the conductor 11. The auxiliary switch 42 is closed when the circuit breaker 3 is open and is adapted to open when the circuit breaker has been operated to closed and latched position, 90 there being a lost motion connection between 95

the circuit breaker operating means and the switch 42, as indicated. The switch 41 may be operated in any suitable fashion so that it is closed only when it is desired to synchronize the generator and the line.

Leading from the conductor 11 is a conductor 17 between which and control bus 12 a motor 18 is connected. This motor is thus fed from transformer 9. Connected between the conductor 17 and the control bus 10 is another motor 19, this motor being thus fed from transformer 8. The motors 18 and 19 may be synchronous motors or synchronous induction motors, or, generally, motors the speed of which will vary synchronously with the frequency of the line and generator respectively. The motor 18 has an insulating disk 20 mounted on the shaft thereof. The disk 20 as shown in Fig. 2 is provided with a plurality of contacts 21, 22, 23 and 24 which are flush with the face of the disk and are all connected electrically to a slip ring 27. Facing the disk 20 is another disk 25 which is here shown as mounted on the shaft of motor 19. The disk 25 carries a contact 26 which projects slightly from the face of the disk 25 toward the face of disk 20, and is adapted to make contact with one or the other of the contacts on disk 20. The contact 26 is electrically connected to a slip ring 28.

A relay 29 is here shown as having one terminal connected to control bus 10, the other terminal being connectible through a resistance 30, a conductor 39, a resistance 31 a conductor 32, to the other terminal of the secondary of transformer 9. In conductor 39 is interposed a contact 38 controlled by an adjustable time limit relay 36. Also interposed in conductor 39 are the slip rings 27 and 28 and the contact 26.

Relay 36 is connected across the control buses 10, 12 through a resistance 37. It will however be noted that one of the terminals of relay 36 as here shown is connected to control bus 10 to the right of contact 16 whereas the other terminal is connected to the control bus 12 to the left of contact 15, for a purpose to be hereinafter set forth. The relay 36 is of any suitable form such that when its operating coil has an E. M. F. less than a predetermined value applied thereto, the contact 38 will begin to move toward the closed position and will complete the closing movement in a predetermined adjustable time.

The relay 29 is provided with two contacts 33, 34, the contact 33 being adapted to complete a conducting path 40 which is connected so as to short-circuit the contacts 38 and any contact made by the contact 26. The contact 33 thus, when closed, serves as a maintaining contact for relay 29. The contact 34 is here shown as adapted to close the circuit of coil 5 through a source here shown as a battery 35.

The operation is as follows. Let it be

assumed that switch 41 is closed and that relay 14 is therefore energized thereby closing contacts 15, 16 and energizing control buses 10, 12. The motors 18, 19 are now operating, the disks 20 and 25 rotating at speeds in accordance with the line and generator frequency respectively. If the generator frequency is not equal to that of the line there will be relative motion between the disks 20 and 25 and consequently the contact 26 will periodically engage the contacts 21, 22, 23 and 24. The generator and line will be in phase when contact 26 is in engagement with contacts 21 or 23, for example, and will be 180 degrees out of phase when contact 26 engages contact 22 or 24, for example. This is the case where the motors 18 and 19 are of the four-pole type. Where some other number of poles is chosen, the number of contacts on the disk 20 will be changed accordingly as will be apparent to those skilled in the art. The relay 36 will be effectively energized whenever the E. M. F. across buses 10, 12 is higher than a predetermined value as determined by the relay itself or the adjustment of resistance 37, or both. When the E. M. F. across buses 10, 12 decreases to a predetermined value the relay 36 will be no longer able to maintain the contact 38 open and this contact consequently begins to move toward the closed position, being retarded in this motion by any suitable means, this being here diagrammatically indicated as a dash pot for the sake of convenience. Since the transformers 8 and 9 are connected to relay 36 so that when the line and generator are in phase there is no E. M. F. across relay 36, the contact 38 will begin to close whenever the generator and line are approaching the in-phase relation and will be held open when the line and generator are out of phase by a predetermined angle. It will therefore be apparent that the E. M. F. across relay 36 will vary periodically from zero to a maximum of about double the line or generator voltage and again to zero, etc.

The variation of E. M. F. across relay 36 is shown diagrammatically in Fig. 4, the ordinates of the curve representing the effective or root mean square values of E. M. F. and the abscissae representing time. The maximum E. M. F. impressed upon relay 36 is here represented as the ordinate E. Assuming that the generator frequency is changing and approaching that of the line the generator and line will at first rapidly go through the in-phase and out-of-phase relations and then less and less rapidly as the generator frequency becomes nearly that of the line. The voltage across relay 36 will therefore vary in the manner as represented by the loops 43, 44, 45 in Fig. 4. Taking loop 43 as an example, the line and generator are in phase where the loop crosses the time axis and are 180 degrees out of phase at the top of the loop. Thus the

width of the base of the loop also represents a change of 360 degrees in phase angle, and as the line and generator frequency approach each other the bases of the loops become longer. Stated in other words, the time rate of change of the phase angle between the generator and line becomes smaller and smaller as the generator frequency is approaching that of the line. Clearly, this time rate of change of phase angle also depends upon the time rate of change of frequency.

If as previously assumed the generator and line are in phase when contact 26 is in engagement with contact 21 the time during which this engagement is maintained will be very brief if the time rate of change of phase angle is large. This is represented in Fig. 4 by the time 53. As the time rate of change of phase angle becomes smaller the time during which contact is made by contact 26 when the generator and line are in phase will become longer as represented by the times 54, 55. It will be understood however that the contacts on the disks 20 and 25 are small so that little relative motion between the disks 25 and 20 is necessary to interrupt the contact. While contact is also made between contact 26 and contacts 22, 24, for example, when the generator and line are 180 degrees out of phase, it will be apparent that relay 29 will not be then energized because contact 38 is held open at that time.

As previously stated the relay 36 is effectively deenergized when the voltage across said relay reaches a predetermined minimum. If a horizontal line is drawn through the loops 43, 44, 45 at a height E_1 above the time axis it will cut the loop 43 in, for example, the point 46. If the height E_1 is taken as the hereinbefore mentioned minimum E. M. F. the contact 38 will begin to close when the E. M. F. across relay 36 reaches the point 46 on loop 43. At this time the generator and line are x degrees out of phase and will be in phase in a time 49. The contact 38 closes after a time 52. It will be noted that the end of this period of time falls after the end of the period of time 53 during which contact 26 is in engagement with contact 21, for example. Thus, the time rate of change of phase angle is too rapid so that it would be inadvisable to connect the generator to the line at this time. The E. M. F. across relay 36 then increases again along loop 44 thereby opening contact 38 when the E. M. F. increases above the line whose ordinate is E_1 . When the E. M. F. again decreases to the value E_1 at point 47, contact 38 again begins to close but, as in the case hereinbefore mentioned, at the time the contact 38 closes, contact at 26 has already been broken as represented by the time 54. When however the time rate of change of phase angle is small enough as represented by loop

45, or by the number of degrees z divided by time 51, the contact 38 begins to close at point 48 and closes at the end of period 52. At this time contact is also being made at 26 as represented by the time 55. Since contacts 26 and 38 are contemporaneously closed relay 29 will be energized and contact 33 will maintain said relay energized as hereinbefore set forth. The closing of contact 34 of relay 29 energizes the coil 5 of circuit breaker 3 thereby connecting the generator to the line. The closing of the circuit breaker opens auxiliary contact 42 thereby deenergizing the relay 14 and disconnecting motors 18 and 19.

It will be noted that while after the opening of relay 14 the relay 36 is no longer supplied by transformers 8 and 9 in opposition, there is a leak circuit for this relay extending from conductor 12 through said relay and resistance 37 through conductor 10, motor 19, conductor 17, conductor 11 to the tap 13. The current flowing through this leak circuit is sufficient to maintain contact 38 open. This is for the purpose of preventing the immediate reclosure of circuit breaker 3 in case the same is tripped out, on overload for example, should the contact 26, when the motors 18 and 19 stop, be in engagement with one of the contacts on disk 20. It will be evident, under such condition, that if contact 38 were in engagement at the time circuit breaker 3 opened, the relay 29 would be at once energized thereby immediately reclosing the circuit breaker, and this would occur possibly at a time when the generator and line were out of phase, since the synchronizer would not have had an opportunity to properly control relay 29.

It will be noted that the connection of relay 29 is such that the upper half of the secondary of transformer 9 and the secondary of transformer 8 are in opposition when the line and generator are 180 degrees out of phase. This prevents improper closure of the circuit breaker if contact 38 should be closed by some accident to the circuit of relay 36, for example, the contact 38 being then closed when the sources are out of phase.

In the foregoing explanation of the operation in connection with Fig. 4, it has been assumed that the E. M. F.'s of the line and generator are equal or substantially equal. It will be apparent that if they are not equal the E. M. F. across relay 36 will not fall to zero. Thus, referring to Fig. 4, this means that the loops 43 etc. will not reach the time axis. Considering loop 45, for example, if such a loop does not reach the time axis the line representing the E. M. F. E_1 will cut the right hand or descending side of the loop later in point of time and therefore the time 52 may end at a time when the period of contact 55 has already ended, if the difference in E. M. F. is more than a predetermined

amount. Therefore the circuit breaker will not be closed under these conditions.

It will be apparent, in general, that since relay 36 closes in a very short time after it is effectively deenergized (as when only the

5 E.M.F. E_1 is impressed thereon) the generator will not have much time to change its speed, or cause a change in the time rate of change of phase angle during this short time. This time (51 for example) measured

10 in degrees of phase difference is approximately 30 degrees as the synchronizer has been used in actual practice, though applicant does not limit himself to this particular value.

15 The hereinbefore mentioned feature is of particular value in getting the generator on the line fast, since there are more times when the time rate of change of phase angle is slow for a short period of time (or for a small change in phase, say 30 degrees)

20 than for a long period (or for a large change in phase, say 90 degrees). Moreover, in prior systems in which the change in phase angle is almost 90 degrees from the time that a given relay acts until it closes its circuit, the time

25 rate of change may be the proper slow rate at the beginning of this change and a faster and improper rate at the end of the change, thereby resulting in improper and unsafe connection of the generator to the line. Such conditions occur in certain types of water wheels the speed of which is somewhat unstable at no load.

30 Referring again to Fig. 4, it will be apparent that if the maximum E.M.F. E is higher or lower (within the usual limits of fluctuation of line and generator E.M.F.) this will not materially change the angle at which the loops meet the time axis. Therefore the influence of the maximum value E on the time of closure of relay 36 is small.

35 It should be understood that it is not desired to limit the invention to the exact details of construction shown and described, for obvious modifications may occur to persons skilled in the art.

40 It is claimed and desired to secure by Letters Patent:

1. In a means responsive to the phase relations of two A. C. sources, two transformers each energized from one of said sources, a control circuit, a contact in said control circuit, means for causing said contacts to close upon occurrence of exact equality of phase between said sources, a second contact in said control circuit, and means serially connected to said transformers for holding said second contact open as long as the vector sum of the E. M. F.'s across corresponding pairs of conductors of said sources is above a predetermined amount.

45 2. In a means responsive to the phase relations of two A. C. sources, two transformers respectively energized from said sources, a control circuit, motor driven contacts opera-

50 tive to energize said control circuit responsive to equality of phase between said sources, a second contact in said control circuit, means responsive to the vector sum of the secondary E. M. F.'s of said transformers for holding said second contact open as long as the vector sum of said E. M. F.'s is above a predetermined amount, and means for retarding the closure of said second contact after said sum has fallen below said predetermined amount. 55

3. In a means responsive to the phase and frequency relations of two A. C. sources, a switch, a circuit for controlling said switch, contacts in said circuit, means for closing said contacts when said sources are in phase and 180 electrical degrees out of phase, said contacts being closed and opened periodically when said sources are of different frequencies, other contacts in said control circuit, means responsive to the vector sum of the E. M. F.'s 60 across corresponding pairs of conductors of said sources for effecting a closure of said other contacts only when said vector sum is below a predetermined amount, and means for retarding the closure of said E. M. F. responsive means. 65

4. In combination, two A. C. sources, a circuit breaker interposed between said sources, a pair of transformers connected across said sources respectively, a pair of synchronously operable motors connected to said transformers respectively, a pair of contacts rotatable in substantially parallel planes by said motors respectively, said contacts being disposed to come into engagement when said sources are in phase, a relay having a contact, means for so feeding said relay from said transformers that when said sources are in phase said relay will be deenergized, and means including a circuit in which said relay 70 contact and said pair of contacts are interposed for causing closure of said circuit breaker only when said pair of contacts come into engagement after said relay has been deenergized for a predetermined time. 75

5. In combination, two A. C. sources, a circuit breaker interposed between said sources, a pair of transformers connected across said sources respectively, a pair of synchronously operable motors connected to said transformers respectively, a pair of contacts rotatable in substantially parallel planes by said motors at the speed of said motors respectively, said contacts being disposed to come into engagement when said sources are in phase, a relay having a contact and having an operating winding so serially connected with said transformers that when said sources are in phase the E. M. F. across said operating winding will be substantially zero, means comprising a retarding device for causing said relay contact to move to its closed position before the E. M. F. across said operating winding reaches zero, and before said rotatable contacts come into engage- 120

ment, and means including a circuit in which said relay contact and said pair of contacts are interposed for causing closure of said circuit breaker.

6. In combination, two A. C. sources, a circuit breaker interposed between said sources, means for closing a contact when said sources are in phase, a second means for closing a second contact when said sources are in phase, means controlled jointly by said contacts for closing said circuit breaker, means including a relay for supplying the two means controlling said contacts with current from both of said sources, means whereby opening of said circuit breaker energizes said relay, and means whereby one of said means controlling one of said contacts is maintained energized when said circuit breaker is closed, irrespective of the phase relations of said sources.

7. In combination, two A. C. sources, a circuit breaker interposed between said sources, means for closing a contact when said sources are in phase, a second means for closing a second contact when said sources are in phase, means controlled jointly by said contacts for closing said circuit breaker, means including a relay for supplying the two means controlling said contacts with current from both of said sources, means whereby opening of said circuit breaker energizes said relay, and means whereby one of said means controlling one of said contacts is supplied with current from one of said sources only, when said circuit breaker is closed.

8. In combination, two A. C. sources, a circuit breaker interposed between said sources, a pair of means for closing two contacts respectively in response to predetermined electrical relations between said sources, means controlled jointly by said contacts for closing said circuit breaker, means controlled by said circuit breaker for supplying both of the means for controlling said contacts with current from both of said sources, and means whereby one of said means controlling one of said contacts is supplied with current from one of said sources only, when said circuit breaker is closed.

9. In combination, two A. C. sources, a circuit breaker interposed between said sources, a pair of means for closing two contacts respectively in response to predetermined electrical relations between said sources, means controlled jointly by said contacts for closing said circuit breaker, means controlled by said circuit breaker for supplying both of the means for controlling said contacts with current from both of said sources, means whereby one of said means controlling one of said contacts is supplied with current from one of said sources only, when said circuit breaker is closed, and means whereby when said circuit breaker is

closed said relay will be energized irrespective of the phase relations of said sources.

10. An automatic synchronizing system comprising in combination, two lines energized with alternating E. M. F.'s of independent frequencies, a switch for interconnecting said lines, a transformer energized from each of said lines, a relay connected in series with both of said transformers and having contacts, a synchronously operable motor energized from each of said transformers, cooperating contacts driven by each of said motors, and means responsive to the closure of said relay contacts and the subsequent closure of said motor driven contacts while said relay contacts are closed for actuating said switch.

11. An automatic synchronizing system comprising in combination, two lines energized with alternating E. M. F.'s of independent frequencies, a switch for interconnecting said lines, two transformers connected to said lines respectively, a relay connected in series with the secondary windings of said transformers, two synchronously operable motors connected to the secondary windings of said transformers respectively, a plurality of contacts driven by one of said motors at a speed equal to that of said motor, a single contact driven by the other of said motors at a speed equal to that of said other of said motors, and means responsive to the contemporaneous actuation of said relay and engagement of said single contact with one of said plurality of contacts for actuating said switch.

12. An automatic synchronizing system comprising in combination, two independent lines energized with alternating E. M. F.'s, two transformers each energized from one of said lines, a delayed action relay so serially energized from both of said transformers that its contacts are actuated in response to approximate phase and E. M. F. equality as between said lines, two synchronously operating motors connected to said transformers respectively, mutually cooperative contacts so directly driven by said motors respectively that said contacts are closed at substantially exact equality of phase and frequency, an electromagnetic switch, and means responsive to the actuation of said relay and the subsequent closure of said mutually cooperative contacts for causing the actuation of said electromagnetic switch.

13. In a synchronizing system, the combination of two lines energized with alternating E. M. F.'s of independent frequencies, two transformers each energized from one of said lines, a switch, a control circuit for said switch, a retarded relay having contacts in said control circuit and having an operating winding connected in series with the secondary windings of said transformers, means for causing said relay contacts to partially

complete said control circuit a predetermined time after the vector sum of the secondary E. M. F.'s of said transformers is below a predetermined value, two synchronous motors energized by said transformers respectively, mutually cooperative contacts driven by said motors and arranged to complete said control circuit in response to phase and frequency equality of said line E. M. F.'s.
